CREME SANDWICH COOKIE

Dewey L. Warren, Hewitt, N.J., and Theodore P. Babiak,
Staten Island, N.Y., assignors to Nabisco, Inc., East
Hanover, N.J.

Filed May 12, 1975, Ser. No. 576,435

Term of patent 14 years

Int. Cl. D1—01

U.S. Cl. D1—15

FIG. 1 is a front elevational view of a creme sandwich cookie showing our new design;

FIG. 2 is a side elevational view thereof as seen from the right of FIG. 1; and

FIG. 3 is a rear elevational view of FIG. 1.

We claim:

The ornamental design for a creme sandwich cookie, substantially as shown.
